UNITED STATES PATENT OFFICE.

ADOLPH SORGE, JR., OF ST. JOSEPH, MICHIGAN.

BOX.

1,190,203.

Specification of Letters Patent.

Patented July 4, 1916.

Application filed February 19, 1912. Serial No. 678,739.

To all whom it may concern:

Be it known that I, ADOLPH SORGE, Jr., a citizen of the United States, and a resident of St. Joseph, in the county of Berrien and State of Michigan, have invented a certain new and useful Improvement in Boxes, of which the following is a specification.

This invention relates to boxes.

The object of the invention is to provide 10 a box or receptacle adapted for dispensing material contained therein in separate measured quantities as wanted for use; and to protect the unused portions of the material remaining in the box or receptacle from contact with the air, which might cause the 15 same to deteriorate.

To this end, a box or receptacle of my invention comprises a plurality of separate units of suitable size to contain a desired 20 predetermined quantity of any material or substance, said units being connected to form a unitary structure, and in such manner that the contents of any succeeding unit may be rendered accessible for use by 25 moving or detaching the preceding adjacent unit.

The device also comprises the various other features and details of construction hereinafter described and claimed.

30 In the accompanying drawing, in which my invention is fully illustrated, Figure 1 is a perspective view of a finished box or receptacle of my invention; Fig. 2 is a vertical, central sectional view thereof; Fig. 3 is a perspective view of one of the units of 35 my improved box or receptacle; Fig. 4 is an enlarged fragmentary sectional view.

Referring now to the drawing, A designates, as a whole, a box or receptacle of my 40 invention, said box or receptacle comprising a plurality of units, each consisting of a separate small box *a*. Said unit boxes *a* are arranged in juxtaposed series, being preferably superposed, and are detachably connected to form a unitary structure, preferably by means of a binder *a'*, which is wrapped around said unit boxes *a*, arranged 45 in series as stated, and securely gummed, pasted or otherwise firmly attached to the 50 sides of all of the units of the series. In practice, the wrapper *a'* preferably consists of a suitable label.

In order that the finished box or receptacle A may present a neat appearance, the 55 sides of the units *a*, to which the wrapper *a'* is applied, are preferably made substan-

tially straight, so that said wrapper *a'* will fit the same smoothly.

While my invention contemplates the use of any usual or approved form of unit boxes 60 *a* comprising a body portion and a cover or closure therefor secured thereto in any desired manner, I prefer the form of units shown in the drawing, each of which consists of a body portion 1 and a closure there- 65 for, consisting of a disk 2 which rests against the end of said body portion 1 and is secured thereto by means of a wrapper 3 at- tached to the side walls of said body portion 1 and folded over and firmly secured 70 to said disk, as by a suitable adhesive. If desired, my invention contemplates provid- ing perforations 4 in the sides or ends of 75 said units *a* to provide for sifting out the contents thereof in using the same, in sub- stantially the manner of an ordinary pepper box. In the preferable construction shown, also, said unit boxes *a* are provided with raised or struck up portions 5 on one of 80 their ends, respectively, and with corre- sponding recesses 6 in their opposite ends adapted to receive said raised or struck up portions 5 of adjacent boxes, thereby forming 85 a male and female joint between adja- cent units, both the sides of said raised por- tions 5 and of said recesses 6 being prefer- ably slightly tapered and the relation being such that said raised portions 5 will snugly nest in the recesses 6. A particular advan- 90 tage of this construction is that the differ- ent units *a* will be centered or positioned relatively to each other and will be tempo- rarily secured together during the process 95 of applying the binding wrappers *a'* there- to. A further advantage of said construc- tion, when an inclosed side or end of said unit boxes, respectively, is perforated, is that, by forming said perforations on either the raised or depressed portions only there- 100 of, the engaging tapered sides of said raised and depressed portions will form a tight closure for the perforated sections of said units.

With a box or receptacle A constructed 105 as described, it is obvious that the contents of each unit *a*, other than the first, will be rendered accessible by merely detaching and removing the preceding adjacent unit, if the end of said unit thereby exposed is perforated, or, if tightly sealed, by detaching the 110 preceding adjacent unit and then opening the exposed side thereof.

Where the exposed side or end of the first unit box *a* is perforated, said perforations will preferably be sealed by a suitable closure, which may be a closed disk *7* secured over the perforated end or side of said first unit box, as by folding the end of the wrapper *a'* over said disk and securing it thereto, as by a suitable adhesive.

I claim:—

- 10 A box, comprising a plurality of separate units detachably connected to form a unitary structure, said units being arranged in series with corresponding sides of succeeding units overlaid and covered by preceding adjacent units, whereby the covered sides of succeeding units will be uncovered and exposed by detaching the preceding adjacent unit, each of said units forming a complete box in itself capable of being utilized inde-
- 15

pendently when detached, and said unit 20 boxes being provided on one of their sides with struck up or raised portions and with corresponding depressions in their opposite sides adapted to receive the raised portion of another box unit, the sides of said raised 25 portions and of said depressions being correspondingly tapered and one thereof being perforated inside of its tapered sides, substantially as described.

In testimony that I claim the foregoing 30 as my invention, I affix my signature in presence of two subscribing witnesses this 16th day of February A. D., 1912.

ADOLPH SORGE, JR.
